UNITED STATES PATENT OFFICE.

NICK E. WILMES, OF SAN FRANCISCO, CALIFORNIA.

VIBRATOR MASSAGE IMPLEMENT.

1,113,070.

Specification of Letters Patent.

Patented Oct. 6, 1914.

Application filed December 6, 1913. Serial No. 805,053.

To all whom it may concern:

Be it known that I, NICK E. WILMES, a citizen of the United States, residing in the city and county of San Francisco and State of California, have invented new and useful Improvements in Vibrator Massage Implements, of which the following is a specification.

This invention relates to a vibrator massage implement.

The object of this invention is to provide a simple, substantial, cheaply manufactured, highly efficient vibrator, which is so constructed that various vibrator applicators may be quickly and easily attached.

Another object of the invention is to provide means for disconnecting the vibrator mechanism; and to provide a socket connection into which rotary massage implements may be inserted and driven by.

Further objects will hereinafter appear.

The invention consists of the parts and the construction and combination of parts as hereinafter more fully described and claimed, having reference to the accompanying drawings, in which—

Figure 1 is a side elevation of the vibrator massage implement. Fig. 2 is a vertical sectional section through same. Fig. 3 is a plan cross section on line 3—3, Fig. 2. Fig. 4 is a side elevation of one form of rotary massage applicator.

Referring to the drawings, A indicates a spherical shaped housing having a hollow handle extension 2 of suitable shape and length. Revolubly mounted in journals 3 and 4, mounted in the hollow handle, is a tube 5 having a thrust-collar 6 formed on its lower end which is supported by a lower removable member 7. Suitably secured to the lower end of the hollow shaft or tube 5 is a flexible driving connection 8, and secured to the tube near its upper end is a driving pinion 9 which intermeshes with a pinion 10. The pinion 10 is journaled on a stud-bolt 11 and is formed integral with a larger gear 12 which is so positioned as to intermesh with a pinion 13 loosely journaled upon the tube 5 above the driving pinion 9. The upper face of the pinion 13 is provided with a jaw clutch 14, of any suitable construction, which is provided for the purpose of forming a driving connec-

tion between the gear 13 and the vibrator generally indicated at 15.

The vibrator is here shown as consisting of a hub member 16, having an annular groove 17 formed near its lower end, and a pair of outwardly extending weighted arms 18 formed on its upper end. The groove 17, formed on the hub, is straddled by a forked shifting member 19, secured upon the end of a spring bar 20. The spring bar 20 has notches 21 formed near its lower end which are so positioned as to become engageable with a latch member 22, secured in the casing A, and the bar 20 is otherwise secured with an operating handle 23. The vibrator, consisting of the weighted arms 18 and hub member 16, may be lifted out of engagement with the jaw clutch 14 by simply pressing the bar 20 in an upward direction until the latch 22 engages with the lower notch 21, formed on the bar, and may similarly be moved into driving connection with the gear 13 by pressing the bar 20 in an inward direction and permitting it to drop until the upper notch is engaged. The downward movement of the vibrator is assisted by a coil spring 24 which is interposed between an upper cover 25 and the hub of the vibrator.

The cover 25, inclosing the vibrator 15, with connected driving gears and tube 5, is preferably secured upon the spherical main casing A by a flexible rubber ring 26, having a conical hub extension 27 formed on one side adapted to receive various forms of vibrator applicators, one of which is indicated at 28, Fig. 1. Vibratory movement may be caused by making one of the weighted arms heavier than the other, or by throwing one or the other slightly out of alignment. The vibratory movement thus produced may be transmitted either through the applicator 28 or by placing the casing 5 directly against that portion of the body which is to be treated.

The vibrator here shown is also adapted for transmitting rotary motion to applicators of the type shown in Fig. 4. This is accomplished in the following manner: As before described, it can be seen that the driving shaft 5 consists of a tube which opens through the upper cover member 25. A shank member 29 having a forked mem-

ber 30 formed on its lower end and adapted to receive a revolving applicator 31 of any suitable type on its upper end may thus be inserted through the upper end of the tube. 5 A pin 32 is secured in the tube and is provided for the purpose of forming a driving connection between the shank 29 and the tube 5, and is also provided for the purpose of limiting the downward movement of the 10 shank within the tube. It can thus be seen that revolving movement may be transmitted through the tube 5 to any suitable form of applicator, or such as is shown in Fig. 4, and that either one or the other, or both, 15 may be operated singly or in unison by disengaging the clutch member 14 through the medium of the spring bar 20 and operating handle 23.

The vibratory movement created by the 20 weighted arms 18 of the vibrator may, in this instance, be very efficiently transmitted as practically no vibration is lost through the flexible ring connection 26.

The vibrator is simple in construction and 25 reliable and efficient in operation for the simple reason that all reciprocating members are entirely obviated. All vibratory or rotary movement here transmitted is created by centrifugal force and may, therefore, be simply constructed and of the fewest 30 parts possible.

The materials and finish of the several 35 parts of the vibrator are such as experience and judgment of the manufacturer may dictate.

Having thus described my invention, what I claim and desire to secure by Letters Patent is—

1. The combination in a vibrator, of a casing, a shaft revolubly mounted in said casing, a centrifugal vibrator loosely mounted on said shaft, and means for connecting the vibrator with the shaft.

2. The combination in a vibrator, of a casing, a shaft revolubly mounted in said casing, a centrifugal vibrator loosely mounted on said shaft, means for connecting the vibrator with the shaft, a cover member inclosing the vibrator through which the 50 upper end of the shaft extends, and a flexible rubber ring securing the cover to the casing.

3. The combination in a vibrator, of a casing, a shaft revolubly mounted in said casing, a centrifugal vibrator loosely mounted on said shaft, and means for increasing the speed of the vibrator with relation to the shaft.

4. The combination in a vibrator, of a casing, a shaft revolubly mounted in said casing, a centrifugal vibrator loosely mounted on said shaft, means for connecting the vibrator with the shaft, a socket formed in the upper end of the shaft, a shank insert-

ible into said socket, and means for locking 65 the shank to revolve with the shaft.

5. The combination in a vibrator, of a casing, a shaft revolubly mounted in said casing, a centrifugal vibrator loosely mounted on said shaft, means for connecting the vibrator with the shaft, a socket formed in the upper end of the shaft, a shank insertible into said socket, means for locking the shank to revolve with the shaft, and means for securing a massage implement on the 75 upper end of the shank.

6. A vibrator comprising in combination, a spherical shaped casing having a handle formed thereon, a shaft revolubly mounted in the handle and casing, a driving pinion 80 secured on the shaft, a driven pinion loosely mounted on the shaft above the driving pinion, a pair of connected gears intermeshing with the driving and driven pinions, a hub member revolubly mounted on the shaft, a 85 pair of weighted arms fixed on the hub member, means for locking the hub to the driven pinion, and means for holding the hub member out of engagement with the driven pinion.

7. A vibrator comprising in combination, a spherical shaped casing having a handle formed thereon, a shaft revolubly mounted in the handle and casing, a driving pinion secured on the shaft, a driven pinion loosely 95 mounted on the shaft above the driving pinion, a pair of connected gears intermeshing with the driving and driven pinions, a hub member revolubly mounted on the shaft, a pair of weighted arms fixed on the hub member, jaw clutch faces formed on the lower side of the hub member and the upper side of the driven pinion respectively, means for holding the clutches in engagement to drive the hub member with connected 100 weighted arms, a forked arm straddling the hub member, a spring bar secured to the forked arm, means for raising the spring bar with connected forked arm and hub member to hold the jaw clutches out of engagement, and means for locking the spring bar in the raised position.

8. A vibrator comprising in combination, a spherical shaped casing having a handle formed thereon, a shaft revolubly mounted 115 in the handle and casing, a driving pinion secured on the shaft, a driven pinion loosely mounted on the shaft above the driving pinion, a pair of connected gears intermeshing with the driving and driven pinions, a hub 120 member revolubly mounted on the shaft, a pair of weighted arms fixed on the hub member, means for locking the hub to the driven pinion, means for holding the hub member out of engagement with the driven 125 pinion, a spherical shaped cover member inclosing the driving gears with connected mechanism, an opening in the top of the

cover through which the shaft extends, a socket formed in the upper end of the shaft, a pin extending across the socket near the lower end, a shank member adapted to support a massage implement on its outer end insertible into said socket, and a fork on the lower end of the shank adapted to straddle the pin.

In testimony whereof I have hereunto set my hand in the presence of two subscribing witnesses.

NICK E. WILMES.
